UNITED STATES PATENT OFFICE

123,642

DESIGN FOR A DRESS OR SIMILAR ARTICLE

Augusta Waxberg, Bronx, N. Y.

Application September 18, 1940, Serial No. 95,191

Term of patent 3½ years

To the Commissioner of Patents:

Be it known that I, Augusta Waxberg, a citizen of the United States residing at 751 Walton Avenue, Bronx, New York city, in the county of Bronx, and State of New York, have invented a new, original, and ornamental Design for a Dress or Similar Article, of which the following is a specification, reference being had to the accompanying drawing, forming part thereof.

The trimming across the shoulders and around the neck and cuffs comprises three rows of contrasting colored piping.

I claim:

The ornamental design for a dress or similar article, substantially as shown and described.

AUGUSTA WAXBERG.
